UNITED STATES PATENT OFFICE.

GUSTAV A. BADER, OF ROCHESTER, AND CHAUNCEY W. HOWLAND, OF GENEVA, NEW YORK, ASSIGNORS TO THE STANDARD OPTICAL COMPANY, OF GENEVA, NEW YORK, A CORPORATION OF NEW YORK.

WORK-HOLDER FOR LENS-DRILLING MACHINES.

1,162,327.

Specification of Letters Patent.

Patented Nov. 30, 1915.

Application filed March 28, 1913. Serial No. 757,326.

To all whom it may concern:

Be it known that we, GUSTAV A. BADER and CHAUNCEY W. HOWLAND, respectively of Rochester, in the county of Monroe and 5 State of New York, and of Geneva, in the county of Ontario, in the State of New York, have invented new and useful Improvements in Work-Holders for Lens-Drilling Machines, of which the following, taken in connection with the accompanying drawings, is 10 a full, clear, and exact description.

This invention relates to certain improvements in lens drilling machines of the class set forth in our pending applications No. 15 719,950 filed September 12, 1912 and No. 750,428 filed February 24, 1913, in so far as it relates broadly to a lens support which is adjustable horizontally and vertically to different angles relatively to the axis of a 20 rotary and axially movable drill spindle.

In drilling lenses for the reception of mountings and for other purposes, it is customary to drill part way through the lens from one side and then to reverse the lens 25 and drill from the opposite side until the drill point reaches the apex of the previously drilled hole, thus forming an aperture which is shaped somewhat like an hour-glass or contracted at the meeting ends of the two 30 drill holes after which the contracted portion is reamed and finished to the desired size by means of a reamer and frequently results in breaking away the adjacent portions of the lens between the hole and rim.

The main object, therefore, of our present 35 invention is to provide a lens drilling machine by which the holes for the mountings may be easily and quickly drilled from opposite sides of the lens with perfect accuracy 40 to finish the hole with the drill without the additional operation of reaming and without liability of breaking either the lens or drill even in the hands of unskilled or careless operators.

Another object is to enable the lens 45 holder with the lens thereon to be adjusted horizontally so as to bring the mechanical axis of the lens to the same angle at either side of its neutral position by a single gage 50 setting of the lens holder so that when the lens support is set to drill a lens part-way through from one side a predetermined distance off-center, such lens may be reversed in the holder and the latter adjusted angularly

in the opposite direction until automatically 55 stopped and then redrilled from the opposite side with the assurance that the two drill holes from opposite sides will be in exact alinement.

Another object is to obviate as far as possible 60 the use of screws and similar fastening means in assembling the various parts of the lens support and its coöperating adjuncts.

Other objects and uses relating to specific 65 parts of the machine will be brought out in the following description.

In the drawings:—Figure 1 is a side elevation of a lens drilling machine embodying the various features of our invention. Fig. 2 is a horizontal sectional view taken on line 70 2—2, Fig. 1. Fig. 3 is a vertical sectional view of the lens support taken on line 3—3, Fig. 1. Figs. 4 and 5 are horizontal sectional views of portions of the mechanism shown in Fig. 3. Fig. 6 is a top plan of a horizontally 75 adjustable portion of the lens support in position for drilling the lens off-center from one side, the dotted lines indicating the position of adjustment for completing the drill hole from the opposite side. Figs. 7 and 8 80 are perspective views of the detached lens clamping plates, a portion of Fig. 7 being broken away to show the vertical slots in the end thereof. Fig. 9 is a perspective view of the detached lens centering and decentering 85 block. Fig. 10 is a perspective view of the detached base block for receiving and supporting the block shown in Fig. 9. Fig. 11 is a perspective view of the detached gage 90 plate for regulating the centering and decentering of the lens. Fig. 12 is a perspective view of the detached locking plate for the lens centering and decentering block, shown in Fig. 9. Fig. 13 is a transverse 95 vertical sectional view through a portion of the workholder showing more particularly the lens rest and drill as operating upon a lens. Fig. 14 is a face view of the adjusting means for the edge-limiting stop and adjacent portions of the drilling machine. 100 Fig. 15 is a vertical sectional view through the connections between the rock arm and main operating lever for raising and lowering the drill, showing more particularly the connection between said rock arm and vertical guide rod by which the drill spindle is raised and lowered.

This drilling machine comprises an up-

right standard —1— preferably of cast metal having an integral supporting base —2— and integral forwardly projecting arms or brackets —3— and —4— spaced some distance apart one above the other near the upper end thereof, the rear side of the upper portion of the standard being provided with vertical ways —5— upon which is mounted a vertically movable bracket —6— carrying a horizontal shaft —7— upon which is mounted a pair of idler sheaves —8— for receiving a driving belt (not shown).

The forward ends of the arms —3— and —4— are provided with vertically aligned journal bearings —10— for receiving a vertically disposed revoluble drill spindle —11— having its lower end provided with a drill —13—, the upper end of said drill 20 spindle being journaled in a yoke —15— which is disposed some distance above the upper arm or bracket —4— and is secured to the upper end of a vertical guide rod —16—. This guide rod is slidable endwise in vertically aligned ways —17— and extends a short distance below the lower arm —3— and together with the yoke —15— constitutes what may be termed the supporting frame for the drill spindle for moving the latter axially.

A pulley —18— is secured to the intermediate portion of the drill spindle —11— between the arms or brackets —3— and —4— and is adapted to be driven by the belt previously mentioned which passes around the sheaves —8— and is adapted to be connected to any available source of power, not necessary to herein illustrate or describe.

40 *Work holder.*—Suitable means is provided for supporting the lens in a horizontal plane or at right angles to the axis of the drill spindle and also for supporting it at an angle above or below such horizontal position or at different angles relatively to the axis of the drill spindle according to the contour of the lens; (that is, whether plain or toric), and also for adjusting the lens horizontally to different angles 45 so as to drill the same in the major axis or at either side thereof. This lens holding means comprises a bracket —20— having a rearwardly projecting spindle —21— journaled in a suitable bearing —22— in the intermediate portion of the standard —1— so as to enable the bracket to be adjusted rotarily or tilted vertically to different angles. The front end of the spindle —21— at its junction with the bracket —22— is enlarged to form an annular shoulder —23— abutting against the adjacent face of the standard and is preferably graduated to indicate the degree of angular adjustment, the rear end of the spindle being provided with 60 a removable shoulder or washer —24— and

clamping screw —25— which together with the shoulder —23— hold the spindle and bracket in operative positions against axial movement. The journal bearing for the bracket —20— is located a sufficient distance 70 to the rear of the drill spindle to afford ample clearance for the manipulation of the lens as —a— in the lens clamp hereinafter described, the axis of movement of the bracket —20— being disposed in the same 75 vertical plane from front to rear as that of the drill spindle and also in approximately the same horizontal plane as the lens rest presently described, said bracket being held in its adjusted position by a set screw 80 —25—. The object of this vertical angular adjustment of the supporting bracket —20— of the lens holder is to enable the portion of the lens which is to be drilled to be brought into a horizontal plane at right 85 angles to the axis of the drill spindle either in the major axis or at either side thereof. The bracket —20— extends downwardly from its supporting spindle —21— and is provided with a forwardly projecting horizontal offset —26— underlying the drill spindle transversely of the axis thereof for receiving and supporting a base block —27— forming a part of the lens holder and 90 screwed to the upper face of the offset 95 —26— of the bracket —20— by suitable fastening means as screws —28—.

The base block —27— and its supporting arm —26— extend laterally a greater distance to one side (preferably the left-hand side) of the axis of the drill spindle than to the other side so as to afford ample support for the adjustable lens clamps in drilling the lens close to the right hand edge thereof, said block being provided with a raised portion —29— having lengthwise ribs —30— and —31— near the edges thereof but spaced some distance apart to form an intervening relatively shallow recess —32— for receiving and guiding a horizontally adjustable drill 105 centering and de-centering gage plate —33— shown more clearly in Fig. 4, the intermediate portion of the rib —31— being cut away to form a recess —34— in which the operating arm as —35— of the centering 110 and de-centering plate is movable.

The front side of the raised portion —29— of the base plate —27— is provided with a laterally projecting lengthwise rib —36— having graduations —37— coacting with an 120 index on the operating arm —35— of the gage plate —33— to indicate the point at which the lens is to be drilled relatively to the major axis of such lens. For this purpose, the right-hand end of the gage plate 125 —33— is provided with a V-shaped slot —38— for receiving a stud or stop pin —39— in a superposed laterally swinging drill centering block —40— which is detachably mounted on the upper side of the base 130

block —27— to swing horizontally or laterally about an axis some distance to one side (in this instance left-hand side) of the axis of the drill spindle, as shown more clearly in Fig. 3.

5 The base block —27— and laterally swinging block —40— are preferably made of die castings and adapted to be detachably connected without the use of screws, rivets or bolts, and for this purpose the right-hand end of the raised portion —29— is provided with a central semi-circular journal bearing —41— some distance to the left-hand side of the axis of the drill spindle and having its lower end enlarged or undercut for interlocking engagement with a journal stud —42— projecting downwardly from the underside of the centering block —40—, the lower end of the stud —42— having an enlarged semi-circular flange fitting in the enlarged portion of the journal bearing —41— so as to hold the centering block —40— on the base block —27— against upward displacement when in operative position.

25 The opposite or left-hand end of the base block —27— is provided with a horizontally extending transverse groove —43— concentric with the axis of the journal bearing —41— for receiving a toothed rack —44— on the adjacent end of the centering block —40—, said rack being also concentric with the axis of the journal bearing —41—.

The left-hand end of the raised portion —29— of the base block —27— and corresponding end of the centering block —40— are also concentric with the axis of the journal bearing —41—, said end of the centering block —40— being extended under and downwardly across the corresponding end 35 of the raised portion —29— and preferably extends from side to side thereof.

The groove —43— in which the rack —44— is movable is open at both ends so as to allow the centering block —40— to be rocked laterally about the axis of the bearing —41— so as to disengage the centering block from the base block —27— when the gage plate —33— is moved to the left out of the path of the stop pin —39—.

50 The portions of the gage block —33— at opposite sides of the V-shaped slot —38— constitute stop faces converging from the inner end toward the opposite end of the plate, the point of convergence also forming a limiting stop fitting closely against the pin —39— for locking the centering block —40— so as to drill the lens on the center or major axis and when the gage plate —33— is in this position, its index registers

55 with the zero graduation —37—. These inclined stop faces are disposed at the same angle with and at opposite sides of a plane drawn through the axes of the bearing —41— and drill spindle when the centering block is in its normal position for drilling

in the major axis of the lens and having stepped bearings —33—.

By shifting the gage block to the left a predetermined distance indicated by the 70 graduations —37— and withdrawing the locking bolt —46—, the centering block —40— with the lens thereon may be rocked laterally about its axis until limited by the stop pin —39— engaging one of the stepped 75 stops of the gage plate, thereby bringing the lens into position to drill part way through it such predetermined distance to one side of its center or major axis, and with the same setting of the gage plate, the lens may be inverted on the holder and the centering 80 block —40— rocked in the opposite direction until again limited by the stop pin —39—, thereby bringing the previously drilled part of the lens in exact alinement with the drill 85 ready to finish the drilling of the hole through the lens. In like manner the gage plate —33— may be adjusted for drilling the lens at any predetermined distance indicated by the graduations —37— at either side of the center or major axis with the assurance 90 that the drill holes from opposite sides of the lens will always be in exact alinement with a single setting of the gage plate.

A pair of lens clamping plates —50— and —51— are slidably mounted upon the upper face of the centering block —40— and are each provided with a pair of roller studs —52— and —53— for properly centering the lens with its major axis in a medial line 100 between the pins of each pair, the outward movement of the plate —50— being limited by a stop pin —40—. These clamping plates —50— and —51— are slidably interlocked with the block —40— so as to be easily and quickly removed when desired, and for this purpose the clamping plate —50— is provided with a head —54— and longitudinally extending arms —55— spaced some distance apart and terminating in 105 standing flanges —56— upon which the lens clamping studs —52— are mounted, the arms —55— being adapted to slide in lengthwise grooves —59— in opposite sides of the centering block —40—. The other lens clamping plate —51— is slidably mounted 110 upon the upper face of the centering block —40— and is provided with opposite longitudinal flanges —60— extending downwardly at the sides of the block —40— and arms —55— to the clamping plate —50—, 115 arms —55— to the clamping plate —50—, said flanges —60— being provided with inwardly projecting lengthwise ribs —61— underlying the opposite longitudinal arms —55— along which they are movable.

The lens clamping studs —53— are 120 mounted directly upon the inner end of the plate —51—, the opposite end of said plate extending downwardly across the outer end 125 face of the head —54— of the clamping plate —50— and is provided with a pair of 130

slots —62— spaced equi-distant apart from the center of the plate for receiving suitable attaching members for a pair of springs —63— shown more clearly in Fig. 5. These springs serve to connect the lens clamping plates —50— and —51— and are preferably arranged in lengthwise grooves in the adjacent faces of the clamping member —50— and block —40—, the inner ends of the springs being attached to pins —64— on the clamping plate —50—, while the outer ends of the springs are attached to suitable rods —65— which enter the slots —62— and are provided with heads —66— engaging the outer end face of the lens clamping member —51— so that the springs normally tend to draw the clamping members —50— and —51— toward each other to hold their studs —52— and —53— in engagement with the perimeter of the lens as —a—, Fig. 3. These studs are not only free to roll upon their supporting pins to reduce friction but are preferably removable to permit them to be replaced by new ones when worn.

25 The springs —63— are located in registering lengthwise grooves in the inner faces of the arms —55— and adjacent faces of the block —40— equi-distant from and at opposite sides of the longitudinal center of said block so as to move the lens clamping members in exact parallelism with said longitudinal center and therefore parallel with the major axis of the lens to more accurately center the lens on the support, the outer ends 35 of the springs —63— and attaching rod —65— being passed through registering apertures in the adjacent ends of the clamping plates —50— and —51—. These clamping plates are drawn under yielding pressure toward an edge limiting stop —67— by means of a spring —68— to hold the edge of the lens —a— against said stop during the drilling operation.

40

45 The spring —68— is centrally disposed within registering openings in the block —40— and outer ends of the clamping members —50— and —51— and has its inner end attached to a suitable fastening member —69— and its outer end connected to an attaching member —70— similar to the attaching member —66— in that its outer end is provided with a head —71— engaged with the outer end face of the clamping member —51—. The attaching member —70— is 55 also seated in a slot —72— in the outer end of the clamping member —51— and opens from the bottom thereof. These open-sided slots for receiving the attaching members —66— and —71— permit the clamping plate —51— to be removed without disengaging the springs —63— and —68— from their respective fastening members —64— and —69—.

55 The upper faces of the lens clamping members —50— and —51— adjacent the

posts —52— and —53— are disposed in the same plane parallel with the outer face of the block —40— and guides along which said clamping members are adapted to move. When inserting a lens between the clamping pins —52— and —53—, the clamping plates —50— and —51— are drawn apart by hand against the action of the springs —63— a sufficient distance to allow the lens to enter between the pins and when the clamping members are released, said springs automatically draw the clamping members toward each other to cause the pins —52— and —53— to engage the perimeter of the lens and hold it in operative position upon the clamping plates.

60 The springs —63— and —68— are comparatively light and under light tension just sufficient to draw the lens clamps toward each other with sufficient positiveness to center and hold the lens and to carry said lens into engagement with the stop pin —67—, but it is desirable to provide some means for temporarily holding the lens clamps some distance to the left of the drill spindle 65 during the placing of the lens between the clamping pins, and for this purpose we have provided the rear side of the clamping member —51— with a slot —57— in which is pivotally mounted a holding pawl or detent 70 —58— adapted to engage the adjacent end face of the lens centering and decentering block —40—. This detent is shown more clearly in Fig. 2 and consists of a lever centrally pivoted to the adjacent side of the lens clamping plate —51— with opposite ends thereof disposed at an angle to each other so that when in its unlocked position, the locking end will project beyond the back face of the clamping plate —51— to be engaged by the fingers to press it to its locking position when the lens clamps are drawn back, and when in its locked position, the opposite end projects beyond the back face of the clamp —51— to be engaged by the fingers for unlocking, the lower end of the pawl being adapted to engage a shoulder —58'— on the left-hand end of the block —40—.

65 The standard —1— is provided with a forwardly projecting integral arm —75— some distance below the lower arm —3— for supporting the edge stop —67— and a plate —76— which is secured to the underside of the arm —75— and extends laterally 70 across the axis of and under the drill —13— and is provided with an aperture in which is loosely mounted a lens rest —78—. This lens rest preferably consists of a cylindrical pin or post co-axial with the drill 75 spindle and drill and provided with a conical upper end and an enlarged lower end forming a head —79— having a rounding lower bearing face which is concentric with the produced axis of the supporting spindle 80

—21— for the bracket —20— and is adapted to bear against the upper face of the lens centering block —40—.

The upper face of the block —40— therefore forms a support for the lens rest —78— to hold it in operative position in axial alignment with the drill spindle and at the same time permits the block —40— and its supporting bracket —20— to be tilted vertically to different angles without disturbing the position of the lens rest or post —78— which always remains in axial alignment with the drill spindle, the object being to afford a firm bearing for the portion 10 of the lens which is to be drilled during the drilling operation.

The upper lens bearing face of the lens rest —78— is disposed approximately at the intersection of the produced axes of the 20 spindle —21— and drill spindle —11— but is a trifle below the horizontal plane of the spindle —21— so as to support the portion of the lens to be drilled in a horizontal plane or at right angles to the axis of the 25 drill spindle, thereby permitting the lens to be drilled a part way through from opposite sides with the assurance that the opposite drill holes will be in exact alignment.

The stop pin —67— is disposed in the 30 same vertical plane as the axis of the drill spindle but at right angles thereto and is adjustable toward and from said axis to gage the distance at which the lens is to be drilled from the edge thereof.

The stop pin —67— is preferably mounted 35 in an externally threaded sleeve —67'— which is screwed in a threaded opening —80— in the arm —75— and is provided with an operating member —81— by which 40 the sleeve and pin may be adjusted toward and from the produced axis of the drill spindle, the periphery of the operating member —81— being graduated to register with a suitable index on an adjacent projection —82— of the arm —75—.

The inner end of the stop pin —67— is preferably flattened and arranged edgewise vertically and is held in this position by 50 means of an angular locking key —83— having one end inserted in the projection —82— and its other end passed through an aperture in the outer end of the stop pin as shown more clearly in Fig. 2.

The projection —82— preferably consists 55 of a screw engaged with a threaded aperture in the arm —75— to afford means for slightly adjusting the stop pin when necessary to harmonize the reading of the graduations on the operating member —81— with 60 the corresponding distance of the stop pin from the produced axis of the drill spindle.

Suitable means is provided for moving the drill spindle and drill axially so as to 65 drill the lens part way through under yielding pressure, and for this purpose we have

provided a lever —90— which is pivoted at its rear end at —91— to one side of the upper portion of the standard —1— and is provided at its opposite or front end with a suitable handle —92— by which it may be depressed or raised if desired.

The drill spindle and its supporting frame including the guide rod —16— are held in their normal raised positions with the drill away from the lens rest —78— by means of a coil spring —93— encircling said guide rod —16— between the arm —3— and a suitable pin 94 on the rod —16—. A rock arm —96— is fulcrumed on the same pivot —91— co-axial with the lever —90— in close proximity thereto and is engaged with the pin —94— to reciprocate the drill spindle and its supporting frame as the lever —90— is operated in drilling a lens, said lever being movable separately from the rock arm —96—.

The lever —90— is yieldingly connected to the rock arm —96— through the medium of a spring —97— and bell crank lever —98—, the latter being pivoted at —99— to upstanding ears —100— on the rock arm and is provided with a rearwardly projecting apertured heel —101— for receiving an adjusting screw —102— by which the lever —98— may be adjusted to vary the tension 95 of the spring —97—. The object of these connections between the operating lever —90— and drill spindle is to enable the drill to be brought into drilling engagement with the lens under a yielding and more uniform 100 pressure and without liability of breaking the lens. For example, in drilling a lens, the lever —90— is rocked downwardly carrying the rock arm —96— and lever —98— with it against the action of the spring 105 —93— until the drill engages the lens which tends to retard further movement of the rock arm —96—, but permits the lever —90— to be further moved against the action of the spring —97—, thereby applying 110 the drill to the lens under a uniform pressure equal to the tension of the spring —97— and preventing excess pressure or feed of the drill which would tend to crack or break the lens.

115

What we claim is:

1. A lens drilling machine having an axially movable drill spindle, a lens rest co-axial with the drill spindle, and a lens support tiltable to different angles about an axis substantially co-incident with the end of the lens rest nearest the drill at right angles to the axis of the drill spindle, the lower end of the lens resting on said support and being concentric with the axis of movement of said support.

2. A lens drilling machine having an axially movable drill spindle, a lens rest co-axial with the drill spindle, means for holding the lens rest against tilting movement 130

- relatively to its axis, and a lens clamp adjustable rotarily about an axis at substantially right angles to that of the drill spindle and lens rest.
5. 3. A lens drilling machine having an axially movable drill spindle, lens rest consisting of a post co-axial with the spindle and having its end opposite that nearest the drill concentric with a point in its produced axis, and lens-holding means movable vertically about said point and having a portion thereof bearing against said concentric end of the post.
10. 4. A lens drilling machine having an axially movable drill spindle, a lens rest consisting of a post co-axial with the spindle and having its end opposite that nearest the drill concentric with a workholders about a point in its produced axis, and lens holding means adjustable about an axis running through said point at right angles to that of the drill spindle and having a portion thereof bearing against the concentric portion of the lens rest.
15. 5. A work-holder for lens-drilling machines comprising a base block, a laterally swinging member having interlocking connections with the base block, said connections being separable only when the laterally swinging member is moved to a certain position relatively to the base block, means including a locking bolt for locking the laterally swinging member in its adjusted position, and lens-clamping members slidable upon the laterally swinging member.
20. 6. In a lens-drilling machine, in combination with a drill spindle, a lens holder adjustable rotarily about an axis at one side of that of the drill spindle, a stop pin on the holder, a gage plate having opposed stop faces in the path of said pin, and supporting means for the gage plate and lens holder.
25. 7. A lens drilling machine having a drill spindle, a lens clamping device movable about an axis at one side of the produced axis of the drill spindle, a support for the clamping device and means for limiting such movement to different angles including a gage plate slidable on the support and having diverging bearing faces, and a stop pin on the clamping device between and adapted to be engaged by said faces.
30. 8. A lens drilling machine having a drill spindle, an abutment for the edge of the
- lens at one side of the produced axis of the spindle, a lens clamping device movable to and from said abutment and adjustable rotarily about an axis at the opposite side of the produced axis of the spindle, a support for the clamping device and means for limiting the angular adjustment of the lens clamping device comprising a stop pin on the clamping device, and a gage plate on the support having diverging bearing faces at opposite sides of the pin and adjustable toward and from said abutment.
35. 9. A lens drilling machine having a drill spindle and a lens clamping device comprising a pair of relatively movable clamping members, a support for said members, a stop for engaging the edge of the lens, means for forcing both clamping members toward the stop, and separate means for forcing said members into their clamping positions for engaging the lens.
40. 10. A work-holder for lens-drilling machines comprising a supporting base, a laterally swinging member mounted thereon movable to opposite sides of a medial line, a stop pin on the laterally swinging member, a sliding member guided on the base block and provided with opposed stops coacting with opposite sides of the pin equidistant therefrom for limiting the movement of the laterally swinging member in reverse directions, and a lens-clamp mounted on the laterally swinging member.
45. 11. A work-holder for lens-drilling machines comprising a supporting base, a laterally swinging member mounted on the base, means for holding a lens in the vertical plane of the axis of the laterally swinging member, a stop pin in said plane, and an adjustable plate movable parallel with said plane and having a V-shaped recess in one end for receiving said pin, the apex of the recess being disposed in the plane of the pin and the sides of the recess diverging at equal angles therefrom.

In witness whereof we have hereunto set our hands this 20th day of March, 1913.

GUSTAV A. BADER.
CHAUNCEY W. HOWLAND.
